UNITED STATES PATENT OFFICE.

ADAM H. HANEY, OF CHILLICOTHE, OHIO.

COMBINED COSTUMER AND WARDROBE.

1,323,469.

Specification of Letters Patent.

Patented Dec. 2, 1919.

Application filed March 15, 1919. Serial No. 282,770.

To all whom it may concern:

Be it known that I, ADAM H. HANEY, a citizen of the United States, residing at Chillicothe, in the county of Ross and State 5 of Ohio, have invented certain new and useful Improvements in Combined Costumers and Wardrobes, of which the following is a specification, reference being had to the accompanying drawings.

10 This invention relates to a combined costumer and wardrobe, and the aim of the invention is the provision of a device of this kind for receiving various articles of wearing apparel, such as hats, coats, pants, shoes 15 and the like, as well as laundry.

The invention further aims to provide a combined costumer and wardrobe, so constructed as to provide a compartment for hats, a compartment for clothing and shoes, 20 the latter compartment also having means on which laundry, that is, soiled clothes, may be suspended.

More specifically, the invention aims to provide a costumer pedestal or upright provided with supporting legs, a super-imposed shoe shelf, a hat shelf in super-imposed relation to the shoe shelf, and considerably spaced therefrom, to provide a clothing compartment, and hooks on the pedestal in the 25 clothing compartment, and a top member spaced above the hat shelf, whereby a curtain may be suspended therefrom in surrounding relation to the various shelves, in order to provide clothing and hat compartments.

Also more specifically the invention aims to provide improved means for fastening the supporting legs and the shoe shelf to the pedestal or upright, and also means (substantially similar to the first means) for fastening the hat shelf, the hooks, and the top member to the pedestal.

The invention further aims to provide means for suspending a curtain from the top 45 piece, that is by means of a draw string for holding the upper edge portion of the curtain to a beveled marginal flange on the under surface of the top piece, whereby the curtain may be draped in a shirred fashion 50 about the pedestal, thereby causing the clothing and hat compartments to be formed. It is obvious that this curtain may be constructed in sections or in one piece, as the case may be.

55 While the design and construction at present illustrated and set forth is deemed pref-

erable, it is obvious that as a result of a reduction of the invention to a more practical form for commercial purposes, the invention may be susceptible to changes, and the right 60 to these changes is claimed, provided they are comprehended within the scope of what is claimed.

The invention comprises further features and combination of parts, as will be herein-after set forth, shown in the drawings and claimed.

In the drawings:

Figure 1 is a view in perspective of the improved combination customer and wardrobe constructed in accordance with the invention.

Fig. 2 is a vertical sectional view through the same.

Fig. 3 is a perspective view showing the 75 construction utilized whereby a customer is formed, that is without the suspended curtain.

Fig. 4 is an enlarged detail view showing the connections of the hat shelf and hooks 80 with the pedestal or upright.

Fig. 5 is a detail view showing the connections between the shoe shelf and the legs to the bottom of the standard or upright.

Fig. 6 is a detail sectional view of the top 85 piece and the upper part of the standard showing the connection of the curtain to the top piece.

Fig. 7 is a detail perspective view of the upper portion of the upright or standard 1, 90 showing the members 14 and 15 inserted in the slots 10 and 11 and the top piece and the member 12 eliminated.

Referring more especially to the drawings 1 designates an upright or standard. The 95 lower portion of this standard is provided with elongated slots 2 and 3, which extend at right angles to each other. It is to be observed that the slot 2 is of greater length than the slot 3. The purpose of this will be 100 obvious from the disclosure to hereinafter follow. The lower end of the standard or upright is designed to engage the floor surface, when the standard or upright is in upright position. Suitable supporting legs 4 105 are provided. These legs are of arched construction and are arranged at right angles to one another. Furthermore, the legs intersect. In order that the legs may intersect and be connected to each other, the legs are 110 provided with notches 5 and 6. One of the arched supporting legs is first inserted in

the slot 3, whereby its notch 6 may register with the lower part of the slot 2. The other arched supporting leg is then inserted through the slot 2, whereby its notch may 5 register with the slot, and therefore is disposed at right angles to the other leg. The two legs are then brought together, so that the notches of the respective legs will arch the legs, so as to insure a tight and arched 10 joint. The notches 2 and 3 act to prevent lateral displacement of the legs, with relation to each other and relatively to the upright or standard. A suitable wedge 7 is inserted through the upper part of the slot 2. 15 However, before inserting or fixing either of the legs in the slots, a shoe shelf 8, which may be any suitable width, is provided. This shoe shelf 8 is provided with a central opening 9, through which the upright or 20 standard passes. The wedge 7 is then inserted, and by imparting several hammer blows to the wedge, the shelf and the legs may tighten securely in the slots, sufficiently to render them rigid relatively to the standard or upright, and in such wise as to firmly 25 balance the upright or standard. The upper part of the standard is supplied with elongated slots 10 and 11. These slots are in staggered relations, in other words, one offset above the other, and are at right angles, the slot 10 is longer than the slot 11. A hat shelf 12 is provided with a central opening 13, through which the upper part of the standard or upright passes. Members 14 30 and 15 are inserted in the slots 10 and 11, the member 14 passing through the slot 10, and the member 15 through the slot 11. These members are provided with notches 16 and 17 extending at right angles to each other. 35 These notches coöperate with each other, and with the body of the members 14 and 15, whereby a joint between the members may be formed. In other words, the member 15 is first inserted in the slot 11, the member 14 40 is then inserted through the slot 10. The respective notches of the members 14 and 15 are then in registration with their respective slots 10 and 11, so that the notches 16 and 17 may coöperate with each other and with 45 the bodies of the members, whereby they may be interlocked. The hat shelf is then arranged in super-imposed relation to the members 14 and 15, the upright or standard 50 being passed through its opening 13. The members 14 and 15 are provided with hooks 18, on which various articles of wearing apparel may be suspended, or upon which coat or pants hangers or the like may be suspended. A filler or spacing member 19 is 55 then fitted over the standard in a super-imposed relation to the hat shelf, and after which the upper part of the standard or upright is inserted through an opening 20 in the top piece 21. This top piece 21 is dis-

posed in contact with the spacing member 65 or filler 19. A wedge 22 is then inserted through the slot 10, and by several successive hammer blows, this wedge is driven in place, forcing the various parts 14, 15, 12, 19 and 21 70 securely together, thereby producing a structure of sufficient rigidity, as to enable wearing apparel to be hung upon the hooks and hats or the like to be disposed upon the shelf 12, whereby a curtain may be suspended from 75 the top piece 21.

Several cleats 23 are secured by the screws 24 to the under face of the top piece, so as to provide a rectangular shaped depending rib. These cleats are beveled on their outer edge portions, as shown at 25. By beveling 80 the outer edges at an acute angle to the underface of the top piece, it is to be observed that a groove is afforded for the upper edge portion of a suspended curtain 26. The portion of the curtain that engages this groove 85 is hemmed to provide a passage in the hem for the reception of a drawstring 27, whereby the hemmed upper edge portion of the curtain may be drawn securely into the groove 90 formed by the bevel. It is obvious that this curtain is full, consequently it is capable of being Shirred. The curtain is made up of several sections, so that the curtain may be parted at different locations, whereby access 95 may be had to the wearing apparel suspended or hung upon the costumer, or whereby access may be had to the interior of the wardrobe. It is obvious that if desired the curtain may be entirely dispensed with, and the remaining structure utilized 100 as a costumer, *per se*. Also if desired, when the curtain is dispensed with entirely, the hat shelf in the top piece and the shoe shelf 105 may be eliminated. In this case, however, the wedges are constructed of greater width, so as to take up the amount of space that was consumed, when such parts were used. Also when constructing the costumer in this manner, the spacing member 19 is, of course, 110 not employed. One face of the curtain at any suitable location is provided with one or more pockets 28 for the reception of small articles or the like, such as gloves, mufflers and the like. Extending laterally 115 from the standard or upright at any suitable location is a plurality of hooks 29, on which laundry or soiled articles may be suspended.

The top shelf is provided on its under face with depending hooks 39, on which the 120 articles of wearing apparel or wearing apparel hangers may be suspended.

In Fig. 7, the slot 11 is of sufficient length to permit of the insertion of the lower member 15, so that afterward the wedge 15^a may 125 be inserted. It is obvious that the upright or standard 1 may be constructed as shown in Fig. 7, so as to eliminate the use of the

shelf 12 and the top piece 21, while the lower end of the standard may be equipped as shown in Fig. 3.

The invention having been set forth, 5 what is claimed as new and useful is:

1. In a combined costumer and wardrobe, the combination with an upright or standard having its upper and lower ends provided with right angle positioned elongated 10 slots, said slots being offset slightly one above the other, of members having interengaging connections arranged in the slots of the upper end of the standard, intersecting and interengaging legs arranged in the 15 slots at the lower end of the standard, the upper members having hooks, and means for wedging said members and the legs closely in fitting engagement in their respective slots, a shoe shelf mounted on the 20 standard or upright interposed between the wedging means and the legs, a hat shelf in super-imposed relation and in contact with one of the members at the top of the standard, a top piece fitted on the standard below 25 the wedging means, and a spacing element interposed between the top piece and the hat shelf.

2. In a combination costumer and wardrobe, the combination with an upright, of 30 supporting legs therefor, a shoe shelf supported on the standard above and in contact with the legs, the upper end of the standard having elongated intersecting slots at right angles to each other, members 35 engaging said slots at right angles to each

other and provided with interengaging lock connections, said members having hooks, a hat shelf fitted on the standard above and in contact with one of said members, a top piece fitted on the standard, a spacing member 40 between the top piece and the hat shelf, and a wedge extending through one of the slots at the upper end of the standard, wedging the members, the hat shelf and the top piece closely together. 45

3. In a combined costumer and wardrobe, the combination with a standard having supporting legs at its lower end and its upper end provided with intersecting vertical openings at right angles to each other, of 50 detachably connected hook carrying members detachably engaging the right angle openings, a hat shelf engaging the uppermost of the hook carrying members, and through which the standard passes, a top 55 piece engaging on the upper end of the standard, a sleeve fitted on the standard between the top piece and the hat shelf for spacing the shelf and the top piece, and a wedge passing transversely through the upper end of the standard beyond the top piece, thereby wedging the aforesaid elements of construction close together. 60

In testimony whereof I hereunto affix my signature in the presence of two witnesses. 65

ADAM H. HANEY.
